By Sommers & Young Atts.

UNITED STATES PATENT OFFICE

1,986,087

LABYRINTH PACKING

Oscar Anton Wiberg, Finspong, Sweden

Application January 18, 1933, Serial No. 652,383
In Germany January 21, 1932

12 Claims. (Cl. 253—16.5)

This invention relates to labyrinth packings of the kind which comprise annular disks carrying sleeve shaped projections on their sides facing each other with the projections of each disk engaging the spaces between the projections of the other disk. The invention has more particularly reference to packings of this type which are adapted for use in connection with turbines or other machines in which one packing disk is carried by a rotary wheel or a similar element, while the other disk is carried by a stationary part.

The object of the invention is to provide a labyrinth packing of the above said type by which within a given diameter a high sealing effect may be obtained as compared with that of labyrinth packings of hitherto known designs. With this and other objects in view, the packing according to the invention comprises two or more pairs of disks or disk sections which are displaced in such a way with relation to each other that the various pairs of disks or disk sections are, at least in part, in overlapping relation to each other.

25 In the accompanying drawings, two embodiments of labyrinth packings according to this invention are illustrated. Fig. 1 is a cross section of one half of a labyrinth packing according to one embodiment as used in connection with a 30 radial flow steam turbine, part of which is shown in axial section. Fig. 2 is a similar view of a packing according to the other embodiment likewise as used in connection with a radial flow steam turbine.

35 In both of the embodiments shown in the drawings, the labyrinth packing is positioned between a rotary turbine wheel and the steam chest.

With reference to Fig. 1, the numeral 1 indicates one shaft of a radial flow steam turbine having two blade disks rotating in opposite directions. 2 is the blade disk carried by the shaft 1. The other shaft as well as the blade disk carried thereby are not shown in the drawings, as this is unnecessary for the understanding of the invention. The turbine disk 2 carries an additional disk section 2' by means of radial bolts 3. The turbine disk sections 2 and 2' carry the blading 4. 5 represents a steam chamber to which high pressure steam is supplied through pipe 6 and from which said steam is passed to the innermost blade ring of the blading 4. The steam chamber 5 together with a surrounding steam chamber 7 are both contained in the steam chest 8. The chamber 7 is in communication

with an inner stage of the blading 4 to allow the admitting of overloading steam to the blading or the withdrawal of bleeding steam therefrom. The steam chest 8 is bounded on its side facing the turbine disk 2 by a labyrinth packing comprising two sections 9 and 10. Each of these sections comprises two disks, one of which, 11 or 12 respectively, is connected to the turbine disk 2 and rotates therewith, whereas the other disk, 13 or 14 respectively, of each section is connected to the steam chest 8. The packing section 10 is displaced axially with relation to the section 9 so that, in the embodiment shown, it is situated nearer to the blading 4 than the section 9 is. The inner diameter of section 10 is less than the outer diameter of section 9 so that the two packing sections are in overlapping relation to each other almost to the entire radial extent of section 10. The space between the sections 9 and 10 affords a connecting passage 15 between a stage 20 of comparatively low pressure of the blading 4 and an additional steam chamber 16 in the steam chest 8.

The labyrinth packing disk 11 is attached to the turbine disk 2 by means of axially extending bolts 17. Said bolts are inserted from the inner side of turbine disk 2 which will render the attachment of the disk 11 very simple as compared with the methods hitherto used in the mounting of labyrinth packings, according to which the bolts are inserted from the outer side of the labyrinth disk. The labyrinth disk 12 is carried by the turbine disk 2 by means of axial pins 18. For sealing purposes a packing ring 19 is inserted between the disks 2 and 12. In order to clamp the labyrinth disk 12 to the turbine disk 2 with sufficient power, a cylindrical ring 21 is inserted between the labyrinth disk 11 and a part 20 of the labyrinth disk 12 closely fitting in a shoulder formed in the labyrinth turbine disk 2, so that the ring 21 may be pressed against said part 20 under the action of the bolts 17. The ring 21 has also for its purpose to afford a tight joint between the disks 2 and 11 at the passage 15.

The labyrinth disk 13 is connected by well-known means to the cylindrical partitions of the steam chest 8. The labyrinth disk 14 is pivotally connected to the stationary disk 23 of an additional labyrinth packing 24 by means of a flexible connecting member 22 affording a steam tight joint between the disks 14 and 23. Said disks 14 and 23 are carried by the outer circumferential wall 27 of the steam chest 8 through the intermediate of an expansion ring 25 and a set of radial bolts 26. Said expansion ring 25 is insert-

ed between the members 23 and 27, whereas the bolts 26 are mounted to hold a collecting chamber 28 in place with relation to the wall 27. Said collecting chamber communicates with the space 5 29 between the packing sections 10 and 24 and is secured to the stationary disk 23 of packing 24 by means of a set of axial bolts 30. The rotary disk 31 of the packing 24 is attached to the turbine disk 2 by means of a cylindrical member 10 32 providing an outer circumferential wall of space 29.

The labyrinth packing above described is capable of affording an effective reduction of the leakage of steam from the high pressure chamber 15 5 to the atmosphere within a restricted diameter.

In Fig. 2 there is shown a modified embodiment of the invention which is still more effective than that above described.

With reference to Fig. 2, the numeral 40 designates the radial flow blading of a turbine having in addition to the radial flow main blading 40 an axial flow blading comprising two rotary wheels 41 and 42 and the associated sets of guide blades 43 and 44, respectively. The radial flow blading 40 is carried, substantially, by a turbine disk comprising two sections 45 and 46 and, as far as the outermost blade rings are concerned, by the wheel 41 as well. The turbine disk sections 45 and 46 are connected to each other by a set 25 of radial bolts 47. Steam may be admitted to the blading 40 from three separate steam chambers 48, 49 and 50 concentrically surrounding each other in the order stated. Said three steam chambers are all contained in one and the same steam chest, part of which only is illustrated in the drawings, as it may be of a design similar to that shown in Fig. 1. Chamber 48 admits steam of high pressure to the innermost blade ring of the blading 40, from chamber 49 steam of high 30 pressure may be admitted for overloading purposes to an inner stage of the blading and from chamber 50 steam of high pressure may be admitted for the same purpose to a stage of the blading 40 situated at a still greater distance 40 from the axis of the turbine. The chambers 49 and 50 may also be used for bleeding purpose. Provided between the rotary turbine disk 45, 46 and the steam chest containing the chambers 48, 49, 50, is a radially extending labyrinth packing 51. Said packing comprises a disk 52 carried by the rotary turbine disk 45, 46 and another disk 53 carried by the stationary cylindrical partitions 54, 55 and outer wall 56 of the steam chest. The two packing disks 52, 53 as well as the turbine disks 45, 46 are formed with passages 57, 58 through which the steam chambers 49, 50 communicate with the respective inner stages of the blading 40. Situated outside the passage 58 is not only the outermost section of the labyrinth packing 51 but also a separate labyrinth packing 59 which is located substantially between the same inner and outer diameters as the said outermost section is. The labyrinth packing 59 comprises a rotary disk 60 attached to the turbine disk section 46 and a stationary disk 61 attached to stationary parts of the turbine in a way to be hereinafter described. Provided outside the packing 59 so as to communicate with the outer periphery thereof is a chamber 62. Said chamber 62 which will, as a result, receive the steam escaping from packing 59, is connected, at its one end with the outermost section of the blading 40, through radial bores 63, and has at its other 70 end a steam bleeding hole 631 and a packing 64 to

prevent leakage of steam from chamber 62 to the interior of the turbine casing.

The stationary disk 61 of packing 59 carries at its outer periphery a substantially cylindrical wall 65 pivotally connected to a, likewise, cylindrical wall 66 projecting from the stationary disk 67 of the packing 64 by means of a connecting member 68. Said connecting member is adapted to afford a steam tight joint between the walls 65 and 66, and is provided with a cylindrical extension 69 engaging an annular groove formed in the outer wall 56 of the steam chest. The members 65, 66 and 69 may, preferably, be flexible in order that they may be capable of taking care of the variations of the dimensions of the packing disks 61 and 67 due to variations of the temperature. The members 65, 68 and 66 form together with the packing 59 the inner wall of chamber 62, whereas the outer circumferential wall of this chamber is represented by a 10 separate cylindrical member 70 inserted between the rotary disk 71 of the packing 64 and the turbine disk section 46. Inside the extension 65 there is provided a space 72 in communication with the outer end of the packing 51, in which the steam leaking through said packing will be received and from which said steam may pass to the inner end of the packing 59. In the steam channel between space 72 and the inner end of packing 59, as afforded by the space between the rotary disk 52 of packing 51 and the stationary disk 61 of packing 59, labyrinth packing elements are provided, as shown at 73, thereby affording an additional packing to prevent leakage of the steam that has passed the packing 51 and has collected in the space 72. By this feature, a corresponding reduction of the leakage losses will be obtained. The rotary disk 60 of packing 59 carries at its inner circumference a cylindrical extension 74 engaging a groove formed in the disk 52 so as to afford a steam tight joint at that point. Said extension 74 forms, as a result, an outer wall of the steam passage 58 where it passes inside the packings 59 and 73 so as to afford a steam tight sealing between 45 said passage and said packings. As a result, only the packing section 51 is traversed by the passage 58.

What I claim is:—

1. In a radial flow turbine, a rotary wheel with its blading, a stationary steam chest having a plurality of concentric chambers, and a labyrinth packing inserted between said wheel and said steam chest, said packing comprising a plurality of annular coaxial sections in radial overlapping relation to each other, each section including a rotary disk carried by the turbine wheel, a stationary disk carried by the steam chest and a set of concentric sleeve shaped elements alternately carried by one and the other of said disks, one of said sections being located between an outer wall of the steam chest and the turbine wheel, means to carry this section between the inner section of the packing, and the turbine wheel, said carrying means surrounding the inner section and being spaced therefrom by a connecting passage between an inner stage of the turbine blading and a chamber of the steam chest.

2. In a radial flow turbine, a rotary wheel having blading, a steam chest, a set of axially displaced labyrinth packings in series inserted between said wheel and said steam chest, an additional labyrinth packing both axially and radially displaced with relation to said first-mentioned

- packings, each of said packings comprising a stationary annular disk and a rotary annular disk, a substantially cylindrical extension on the stationary disk of the labyrinth packing nearest the 5 rotary turbine wheel, a similar extension on the stationary disk of said additional packing, and a connecting element pivotally connecting said two extensions while affording a steam-tight joint therebetween so as to allow the said extensions 10 to form a tight wall.
3. In a radial flow turbine, a rotary wheel having blading, a steam chest, a set of axially displaced labyrinth packings in series inserted between said wheel and said steam chest, an additional labyrinth packing both axially and radially displaced with relation to said first-mentioned packings, each of said packings comprising a stationary annular disk and a rotary annular disk, a substantially cylindrical extension on the 15 stationary disk of the labyrinth packing nearest the rotary turbine wheel, a similar extension on the stationary disk of said additional packing, a connecting element pivotally connecting said two extensions while affording a steam-tight joint 20 therebetween, said connecting element comprising a ring in pivotal and steam-tight engagement with the free ends of said extensions, and a substantially cylindrical flexible member formed integrally with said ring and engaging said steam 25 chest and carried thereby.
4. In a radial flow turbine, a rotary turbine wheel, a stationary part to the side of said wheel, a main labyrinth packing comprising a disk attached to said wheel, another disk attached to 30 said stationary part, and concentric sleeve shaped elements alternately carried by said disks, and an additional labyrinth packing of less radial length than said main packing also inserted between said wheel and said part, said additional packing being displaced axially with relation to the main packing so as to overlap same radially at the outer periphery thereof, while having substantially the same outer diameter as the main 35 packing.
- 45 5. In a radial flow turbine, a rotary turbine wheel, a stationary part to the side of said wheel, a main labyrinth packing inserted between said wheel and said part, an additional labyrinth packing of less radial length than said main packing also inserted between said wheel and said part, said additional packing being displaced axially with relation to the main packing so as to overlap same radially at the outer periphery thereof, a connecting passage between said packings to 40 connect them in series with each other, and concentric sleeve shaped elements arranged in said passage so as to form a labyrinth path therein.
6. In a radial flow turbine, a rotary wheel, a 50 stationary part to the side of said wheel, a main labyrinth packing and an additional labyrinth packing inserted between said wheel and said part with the additional packing displaced axially with relation to said main packing so as to radially overlap same at the outer portion thereof, each of said packings comprising a stationary disk, a rotary disk and concentric sleeve shaped elements alternately carried by one and the other of said disks, adjacent disks of the packings having such sleeve shaped elements on both of their sides.
7. In a radial flow turbine, a rotary wheel, a 55 stationary steam chest to the side of said wheel, a main labyrinth packing situated between said 60 wheel and inner parts of said steam chest, and an additional labyrinth packing situated between said wheel and an outer wall of said steam chest, said additional packing being displaced axially with relation to the main packing so as to overlap same radially at the outer periphery thereof, the connection between the additional packing and said outer wall including a sleeve shaped member surrounding the main packing.
8. In a radial flow turbine, a rotary wheel, a 65 stationary steam chest to the side of said wheel, a main labyrinth packing comprising a rotary disk attached to the turbine wheel and a stationary disk attached to inner parts of the steam chest, an additional labyrinth packing in series with the main packing comprising a rotary disk carried by the turbine wheel and a stationary disk attached to an outer wall of the steam chest, said additional packing being displaced axially with relation to the main packing so as to overlap same radially at the outer portion thereof, and a ring clamped between the rotary disk of the main packing and the rotary disk of the additional packing to maintain the latter in engagement with the rotary turbine wheel.
9. In a radial flow turbine, a rotary wheel, a 70 stationary steam chest to the side of said wheel, a main labyrinth packing between said wheel and said steam chest comprising a rotary disk attached to said wheel and a stationary disk attached to inner parts of the steam chest, a first additional labyrinth packing in series with said main packing displaced axially with relation thereto so as to overlap same radially at the outer portion thereof, a second additional labyrinth packing in series with the first additional packing, said second additional packing being displaced axially and radially with relation to the first additional packing, the additional packings comprising each a rotary disk connected to the rotary wheel of the turbine and a stationary disk carried by an outer wall of the steam chest, connecting means being provided between said stationary disks and said outer wall to take care of expansion and contraction of said disks due 75 to varying heating.
10. In a radial flow turbine, a rotary wheel, a stationary steam chest to the side of said wheel, a main labyrinth packing comprising a rotary disk carried by said wheel and a stationary disk carried by inner parts of the steam chest, a first additional labyrinth packing in series with the main packing comprising a rotary disk carried by the turbine wheel and a stationary disk carried by an outer wall of the steam chest, said first additional packing being displaced axially with relation to the main packing so as to radially overlap same at the outer portion thereof, a second additional packing in series with said first additional packing, comprising a rotary disk connected to the turbine wheel and a stationary disk connected to the said outer wall of the steam chest, expansion elements to connect the stationary disks of the additional packings to each other, other expansion elements to connect the stationary disk of the second additional packing to said outer wall, an axial connecting passage between the additional packings, a steam collecting chamber in communication with said connecting passage, and a set of radial bolts to connect said collecting chamber to said outer wall so as to allow it to expand radially with relation thereto.
11. In a radial flow turbine, a rotary wheel, a 80 stationary steam chest to the side of said wheel, a main labyrinth packing situated between said 85 wheel and inner parts of said steam chest, and an additional labyrinth packing situated between said wheel and an outer wall of said steam chest, said additional packing being displaced axially with relation to the main packing so as to overlap same radially at the outer periphery thereof, the connection between the additional packing and said outer wall including a sleeve shaped member surrounding the main packing.

a main labyrinth packing between said wheel and said steam chest comprising a rotary disk carried by said wheel and a stationary disk carried by inner parts of the steam chest, an additional packing in series with the main packing comprising a rotary disk carried by the turbine wheel and a stationary disk carried by an outer wall of the steam chest, said additional packing being axially displaced with relation to the main packing as to overlap same radially at the outer portion thereof, a substantially axial steam passage formed through the main packing at a smaller diameter than the inner diameter of the additional packing so as to be surrounded thereby, and a projection on the rotary disk of the additional packing to form a tight sealing between said passage and said surrounding additional packing.

5 10 15

12. In a radial flow turbine, a rotary wheel, a

stationary steam chest to the side of said wheel, a main labyrinth packing between said wheel and said steam chest comprising a rotary disk carried by said wheel and a stationary disk carried by inner parts of the steam chest, an additional packing in series with the main packing comprising a rotary disk carried by the turbine wheel and a stationary disk carried by an outer wall of the steam chest, said additional packing being so displaced with relation to the main packing as to be located between the turbine wheel and the outer portion of the main packing, substantially axial steam passages on opposite sides of the region occupied by said additional packing, and projections on the disks of said additional packing to afford steam tight sealing between said passages and said additional section.
